UNITED STATES PATENT OFFICE

EDWARD W. SEARS, OF KANSAS CITY, MISSOURI

DESIGN FOR A LABEL BLANK

Application filed May 9, 1932. Serial No. 43,755. Term of patent 7 years.

To all whom it may concern:

Be it known that I, EDWARD W. SEARS, a citizen of the United States, residing in Kansas City, Jackson County, Mo., have invented a new, original, and ornamental Design for a Label Blank, of which the following is a specification, reference being had to the accompanying drawing, forming a part hereof.

The figure is a plan view of my label blank,

with its ornamental design features shown in full in the lower portion of the blank, the dot-and-dash lines indicating how the same features extend to the upper edge of the blank.

I claim:

The ornamental design for a label blank substantially as shown and described.

EDWARD W. SEARS.
